DESIGN FOR A SOUVENIR NUTCRACKER

Pierre Tourian, New York, N. Y.

Application March 28, 1939, Serial No. 83,872

Term of patent 3½ years

To all whom it may concern:

Be it known that I, Pierre Tourian, a citizen of France, residing at New York, in the county and State of New York, have invented a new, original, and ornamental Design for a Souvenir Nutcracker, of which the following is a specification, reference being had to the accompanying drawing, forming part thereof.

In the drawing:

Fig. 1 is a side elevational view of a souvenir nutcracker, showing my new design.

Fig. 2 is an end elevational view thereof.

I claim:

The ornamental design for a souvenir nutcracker, as shown.

PIERRE TOURIAN.
